UNITED STATES PATENT OFFICE.

PETER CHRISTMAN, OF GREEN BAY, WISCONSIN.

PUMP.

1,054,174.

Specification of Letters Patent.

Patented Feb. 25, 1913.

Application filed April 18, 1912. Serial No. 691,552.

To all whom it may concern:

Be it known that I, PETER CHRISTMAN, a citizen of the United States, residing at Green Bay, in the county of Brown and State of Wisconsin, have invented certain new and useful Improvements in Pumps; and I do declare the following to be a full, clear, and exact description of the invention, such as will enable others skilled in the art to which it appertains to make and use the same.

This invention relates to improvements in pumps.

One object of the invention is to provide a submerged pump having an improved construction and arrangement of intake and discharging mechanism capable of taking in and delivering large quantities of water with a minimum amount of power.

Another object is to provide a pump of this character which will be simple, strong and durable in construction, efficient and reliable in operation and well adapted to the purpose for which it is designed.

With these and other objects in view, the invention consists of certain novel features of construction, and the combination and arrangement of parts as will be more fully described and claimed.

In the accompanying drawings; Figure 1 is a perspective view of my improved pumping mechanism with the top plate or upper end of the pumping cylinder removed; Fig. 2 is a central vertical section of the pump cylinder or lower end of the delivery pipe; Fig. 3 is a top plan view of the pumping cylinder; Fig. 4 is a horizontal sectional view of the same.

In the embodiment of the invention, I provide a pump cylinder 1 closed at its lower end by a bottom plate or head 2 having thereon a centrally disposed step bearing 3. The upper end of the cylinder 1 is exteriorly threaded and has screwed thereon an upper head 4 having a downwardly projecting annular flange 5 threaded on its inner side to engage the threaded upper end of the cylinder 1. On the head 4 is an upwardly projecting annular flange 6 the diameter of which is slightly less than the diameter of the head as shown. In the center of the head 4 is a bearing opening for the pump operating shaft 7 which projects therethrough and extends downwardly through

the cylinder and has its lower end revolvably mounted in the step bearing 3 in the bottom

or lower head 2 of the cylinder. The head 4 is provided on its upper side around the bearing opening with a stuffing box 8 which provides a fluid tight joint between the shaft 60 and head of the cylinder. The upper end of the shaft 7 projects a suitable distance above the top of the cylinder and has its upper end squared as at 9 to receive a squared socket in the lower end of an extension shaft 10 which may be of any suitable length and extends to the top of the well.

In the head or top plate 4 of the cylinder is an annular series of water discharging 70 ports 11 each of which is closed by a separate flap valve 12, said valves being preferably provided on their inner edges with hinge members 13 which are engaged with hinge members 14 on the upper side of the head 4 75 as shown. By hingedly connecting the valves in the manner described they will swing upwardly from the pressure of the water forced upwardly through the ports from the cylinder as will be hereinafter 80 more fully described. In one side of the cylinder 1 is a vertically disposed elongated water inlet opening 15 which opens into a receiving chamber 16 in the pumping cylinder, said chamber being preferably formed 85 by vertically disposed diverging side walls 17 which join or are formed integral at their inner edges adjacent to the shaft 7 and at their outer edges closely engage or are formed integral with the inner sides of 90 the cylinder thereby forming between themselves a vertically disposed passage which is V-shaped in cross section and extends from the bottom to the top of the cylinder.

In the side walls 17 of the receiving chamber 16 are elongated vertically disposed water discharging ports 18 and 19. The port 18 is closed by a vertically disposed flap valve 20 while the port 19 is closed by a similar valve 21. The top or upper end 95 of the receiving chamber 16 is closed by a triangular shaped top 23 in the opposite edges of which are semi-circular notches 24 the purpose of which will be hereinafter described.

Fixedly mounted on or formed integral with the shaft 7 is a radially projecting piston wing or blade 25 which extends outwardly to the inner surface of the cylinder and has in its outer edge a vertically disposed groove 26 in which is arranged a packing strip 27. The packing strip 27

forms a fluid tight engagement between the outer edge of the wing or blade 25 and the inner surface of the cylinder. The upper end of the wing or blade 25 fits closely 5 against the under side of the upper head 4 of the cylinder and on the opposite sides of the blade at its upper end and projecting in opposite directions are port covering lugs 28 the purpose of which will be hereininafter described. Connected with the upper end of the cylinder is delivery pipe 29 the lower end of which preferably fits over and forms a fluid tight engagement with the upwardly projecting flange 6 of the head 4. 10 The pipe 29 extends upwardly to the top of the well or body of water in which the pump is submerged and may be of any desired length for conveying and discharging the water at the desired point. 15

20 In the operation of the pump the shaft 7 and the wing or blade 25 are oscillated or turned first in one direction and then in the other by any suitable operating mechanism (not shown). When the wing or 25 blade 25 is turned in the direction shown by the full line arrow *a* in Fig. 4 of the drawing, a suction is created between the blade and one side of the chamber 16 which will open the flap valve 21 of the port 19 30 and will draw a charge of water through the receiving chamber into the cylinder on this side of the piston wing. While the water is thus being drawn into the cylinder on this side of the piston blade or wing, 35 the water between the opposite side of the piston and the adjacent side of the receiving chamber will be forced out through the ports 11 and into the delivery pipe above the cylinder. In thus discharging, the water 40 will lift the valves 12 ahead of the piston while the suction action of the piston will close and hold the valves 12 in closed position as they are passed by the piston in its oscillating movement. When the piston is 45 moving in the direction described it will be understood that the force of the water compressed by the piston will close and hold the flap valve 20 in close engagement with the port 18 in this side of the receiving 50 chamber. When the piston has completed its stroke in this direction and has been brought into engagement with this side of the chamber, said piston is swung back by its operating mechanism in the opposite 55 direction as shown by the dotted line arrow *b* in Fig. 4 and when moving in this direction the valve 21 of the port 19 will be closed while the valve 20 of the port 18 in the opposite side of the receiving chamber will be open and water will be drawn 60 into this side of the cylinder while the water previously drawn in the opposite side will be forced out through the discharge ports 11 as will be understood.

65 In order to prevent the water from the

delivery pipe 29 from running back into the cylinder should any of the valves 12 of the ports 11 fail to close quickly enough when the piston wing or blade 25 passes beneath the same, I provide said piston wing with the port covering lugs 28 hereinbefore referred to said lugs passing beneath the ports and forming a fluid tight engagement with the inner side of the head 4, thus keeping the ports covered for a brief period after the upper edge of the piston wing has passed beneath the same, and giving the valve time to close tightly which will prevent the water in the delivery pipe from running back into the cylinder behind the piston. The semi-circular recesses 24 in the top of the water receiving chamber of the cylinder are provided to receive the port covering lugs 28 on the piston blade thereby permitting the blade to be swung into close engagement 70 with the opposite sides of the water receiving chamber as will be readily understood. 75

80

85

90

95

100

By constructing and arranging the water inlet ports in the manner described it will be seen that each operation of the piston will draw large quantities of water into the cylinder and by providing a plurality of discharge ports arranged as herein shown and described the water drawn into the cylinder by the piston will be forced out through said ports and the operation of the wing or blade in forcing the water out through said ports will require a comparatively small amount of power.

From the foregoing description taken in connection with the accompanying drawings, the construction and operation of the invention will be readily understood without requiring a more extended explanation. 105

110

Various changes in the form, proportion and the minor details of construction may be resorted to without departing from the principle or sacrificing any of the advantages of the invention as shown.

115

Having thus described my invention, what I claim is:

120

125

130

1. A pump of the character described comprising a cylinder having therein a longitudinally disposed inlet port and a plurality of water discharging ports, a water receiving chamber arranged in the cylinder and communicating with said inlet port, said chamber having in its sides, water discharging ports, valves to close the latter, a piston operating shaft, a piston wing operated by said shaft and adapted to be oscillated in the cylinder whereby water is drawn into the same on one side of said piston and forced out of the cylinder on the opposite side of the piston, the upper portion of said piston wing being adapted for engagement with the water discharging ports for the purpose described.

2. In a pump of the character described,

- a cylinder having therein a water inlet port, a water receiving chamber arranged over said port and having in its opposite sides water discharging ports, valves to close said 5 ports, a head on the upper end of said cylinder, said head having therein a plurality of water discharging ports, valves adapted to close said ports, a piston operating shaft revolvably mounted in said cylinder, a piston 10 wing carried by said shaft and having a fluid tight engagement with the inner surface of the cylinder whereby when said wing is swung in one direction water will be drawn into the cylinder from said receiving 15 chamber on one side of the piston and forced out through the discharge ports of the cylinder on the opposite side of the piston, and lugs arranged on the upper end of said piston wing and projecting beyond the sides 20 of the same for covering the water discharging ports.
3. In a pump of the character described, a cylinder having therein a water inlet port, a water receiving chamber arranged over 25 said port and having in its opposite sides water discharging ports, valves to close said ports, a head on the upper end of said cylinder, said head having therein a plurality of water discharging ports, valves adapted to 30 close said ports, a piston operating shaft revolvably mounted in said cylinder, a piston wing carried by said shaft and having a fluid tight engagement with the inner surface of the cylinder whereby when said wing 35 is swung in one direction the water will be drawn into the cylinder from said receiving chamber on one side of the piston and forced out through the discharge ports of the cylinder on the opposite side of the piston, and 40 port closing lugs carried by the upper end of said piston wing, said lugs having a fluid tight engagement with the inner side of the piston head to cover and close the discharge ports therein for a brief period after the
- piston has passed beneath the ports whereby 45 the water forced through the ports is prevented from reentering the cylinder should the valves of the ports fail to close quickly after the passage of the piston beneath the ports. 50
4. In a pump of the character described, a cylinder having therein a water inlet port, a water receiving chamber arranged over said port and having in its opposite sides water discharging ports, outwardly opening 55 valves to close said ports, a top to close the upper end of said chamber, said top having in its opposite side edges recesses, a head on the upper end of said cylinder having thereon a plurality of water discharging 60 ports, valves to close said ports, a piston operating shaft revolvably mounted in said cylinder, a piston wing carried by said shaft and having a fluid tight engagement with the inner surface of the cylinder whereby 65 when said wing is swung in one direction the water will be drawn from the cylinder from said receiving chamber on one side of the piston and forced out through the discharge ports in the cylinder head on the 70 opposite side of the piston, covering lugs carried by said piston and adapted to close the ports in said cylinder head for a brief period after the piston wing has passed beneath said ports, said lugs being adapted to 75 enter the recesses in the top of the water receiving chamber whereby the piston wing is permitted to swing close to the sides of said chamber, and a water delivering pipe connected with the upper end of the cylinder. 80

In testimony whereof I have hereunto set my hand in presence of two subscribing witnesses.

PETER CHRISTMAN.
